UNITED STATES PATENT OFFICE.

JAMES JOSEPH McGRATH, OF BROOKHAVEN, MISSISSIPPI.

SILK-CLAMP.

SPECIFICATION forming part of Letters Patent No. 664,885, dated January 1, 1901.

Application filed May 2, 1900. Serial No. 15,228. (No model.)

To all whom it may concern:

Be it known that I, JAMES JOSEPH McGRATH, a citizen of the United States, and a resident of Brookhaven, in the county of Lincoln and State of Mississippi, have invented new and useful Improvements in Silk-Clamps, of which the following is a full, clear, and exact description.

The invention has for its object to provide a clamp adapted to bind a bolt of silk and retain the folds in proper position while exhibiting the goods.

In carrying out my invention I provide main clamp-arms and auxiliary inner clamp-arms to obtain a clamping action at two distant points, the inner clamp-arms being of novel form to prevent them from making an impression on the silk when several bolts are superposed. This special arrangement of these inner clamp-arms is to be particularly observed as forming an important element in effecting the purpose of the device without danger of deteriorating the silk.

Reference is to be had to the accompanying drawings, forming a part of this specification, in which similar characters of reference indicate corresponding parts in all the figures.

Figure 1 is a perspective view representing my improved clamp applied to a bolt of silk, the latter being shown partly open to display the goods. Fig. 2 is a side elevation of the clamp on a larger scale, showing its position on the bolt; and Fig. 3 is a perspective view of the clamp detached from the bolt.

The main clamp-arms A are formed in a single piece of suitable spring metal, united at the U-bend a, and have sufficient length to take a proper bearing on the bolt D. The inner clamp-arms B B' are continuous with the main arms and extend inwardly toward the U-bend a. One auxiliary clamp-arm B, it will be observed, extends considerably beyond the companion arm B', and its projecting end b is offset toward the arm B', provid-

ing an extended surface beyond the said arm 45 B' and forming at the base of the offset part a depression b' at a point adjacent to the end of the shorter arm. The result of this arrangement is that neither of the auxiliary arms will be pressed into the silk when several 50 bolts are superposed, and as the inner clamp-arms relieve or modify the clamping action of the ends of the outer arms the bolts and clamps will lie so nearly flat as not to produce indentations in the silk. In exhibiting 55 the goods the clamps preserve the original folds and will prevent the formation of additional creases, which without the clamp are a frequent occurrence and a cause of deterioration of the goods, necessitating a lowering 60 of the selling price.

Having thus described my invention, I claim as new and desire to secure by Letters Patent—

1. A clamp for silk and the like, comprising 65 main clamp-arms, and auxiliary clamp-arms carried by the main clamp-arms and ranging in the opposite direction, said auxiliary clamp-arms being of unequal length and the longer one being offset, presenting a depressed portion 70 opposite the shorter arm and affording a broad projecting end beyond said shorter arm.

2. A clamp for bolts of silk and the like, comprising main and auxiliary clamp-arms, the main arms being convergent to form 75 clamping-surfaces, the said arms being curved outward at the outer ends and being return-bent, forming the auxiliary arms, the latter ranging inward from the outwardly-curved ends of the main arms, the inner ends of the 80 auxiliary arms forming clamping-surfaces.

In testimony whereof I have signed my name to this specification in the presence of two subscribing witnesses.

JAMES JOSEPH McGRATH.
